Primary Examiner — Elizabeth J Oswecki(74) Attorney, Agent, or Firm — Marger Johnson & McCollom PC(57) CLAIM

The ornamental design for a container for deliveries, as shown and described.

DESCRIPTION

FIG. 1 is a front, side perspective view of a container for deliveries showing our new design;

FIG. 2 is a front elevation view thereof;

FIG. 3 is a rear elevation view thereof;

FIG. 4 is a side elevation view thereof;

FIG. 5 is an opposite side elevation view thereof;

FIG. 6 is a top plan view thereof; and,

FIG. 7 is a bottom plan view thereof.

The broken lines shown in the drawings represent portions of the container for deliveries that form no part of the claimed design.

1 Claim, 7 Drawing Sheets(56)
